HARRY J. COLEMAN, OF PELHAM, NEW YORK.

ART OF MOUNTING PHOTO-ENGRAVING PLATES.

Application filed August 20, 1926. Serial No. 130,440.

This invention relates to the art of mounting photo-engraving plates, more particularly as distinguished from the mounting of stereotype plates although the invention may 5 possibly be applied to such type of plates.

It is old in the printing art to provide means for attaching printing plates to their base blocks, in such a manner, however, that the plates cannot be removed without re- 10 moving the blocks when the chase is locked up, or even when the plate and block have been surrounded in the chase by the column rules, type, furniture, leads, or the like, so that the printing form is complete for use 15 except for the fact that it has not been locked up. The usual practice in the printing art in attaching photo-engraving cuts to the base block is, as follows: The picture or the like which is to be photo-engraved to produce 20 a cut, is formed on the surface of the printing plate in well known manner, and the plate stock on which the photo-engraving is produced is larger than the ultimate printing plate, so that it is necessary to run the 25 large stock through a beveling machine which reduces and cuts down the thickness of the plate just up to the lines around the cut which are to form the printing margin around the cut. The reduced portions of the 30 plate are then cut off at three sides of the cut and a thin flange or portion left at the top of the cut, which top flange is outside the printing margin of the cut. It has been customary to drive tacks through this thin top 35 flange and into the base block which is to support the cut. The required base block is of soft metal in order that the tacks may be driven into it, and of course such block must be of the same area as the printing plate 40 which is imposed on and tacked to it. The parts of the plate stock which are removed as stated from three sides of the cut constitute waste metal. Sometimes cement is substituted for tacks, but whether tacks or 45 cement is employed considerable time is wasted in tacking or cementing the plates to their bases, as well as in removing the plates.

The principal objects of the present invention is to anchor photo-engraving cuts into 50 a form of type through the medium of a simple piece of type furniture, which is a separate and independent unit from the base or block upon which the photo-engraving cut is carried, such piece of type furniture being 55 provided with a groove or the like into which a right angle flange on the photo-engraving

cut may be inserted, such right angle flange being preferably produced by bending back at right angles to the back of the cut the flange which is now ordinarily attached or cemented direct to the base block. Through 60 such means various advantages are gained in the photo-engraving art in particular, and they will be found most useful in newspaper picture production or any process where the 65 cuts and type are prepared for matrices, inasmuch as the requirement that the photo-engravings be fastened to their bases by tacking or cementing is eliminated. Another 70 advantage is that it is possible to eliminate the use of soft lead bases, and the present improvements will provide a means of securing the photo-engravings to steel or other hard metal bases. Furthermore, the present 75 invention will prove to be a great time saver, as cuts can be clamped into position in the form without loss of time, and they are ready for the matrix as soon as they are delivered from the engravers, with the elimination of the time and labor of tacking or cementing. 80 Under the present invention the advantage is also gained that the reduced right angle flange at the top of the cut will serve the purpose of obtaining perfect alinement for 85 the cuts when they are placed into position in the form, and also speed will be gained in interchanging cuts from one base to another in make-overs.

With the above general objects and advantages in view, my invention consists of certain features in the novel method and certain features in the means which will be herein-after specifically described and then claimed with reference to the accompanying drawings illustrating a desirable embodiment of 90 the invention, in which:

Fig. 1 is a plan of a photo-engraved plate which has been put through a beveling or planing machine to reduce it at the four sides of the cut and to define the printing margin 100 of the cut in the usual way;

Fig. 2 is a perspective view of the photo-engraving plate after three sides have been cut off to leave a single top flange;

Fig. 3 is a similar perspective view in 105 which the reduced top flange is shown as bent backwardly at right angles to the printing plate;

Fig. 4 is a perspective view of a base block and a grooved piece of furniture or supplemental base block applied to the end thereof;

Fig. 5 is an enlarged sectional view illus-

trating the present improvements and showing the manner in which they are applied to a printing form, except that the entire form is not illustrated; and

5 Fig. 6 is a perspective view of the grooved piece of furniture or supplemental base block.

Referring to Fig. 1, the photo-engraved metal plate 10 appears in the usual form 10 as when it has been grooved or beveled at four sides of the photo-engraved cut to produce reduced edge portions 11, the grooving and beveling producing grooves 12, the inner edges 13 of which define the printing margin surrounding the cut. This is the usual 15 way in which photo-engraved plates are prepared preliminarily to their being mounted on their bases, and one step of the present new method takes advantage of this old 20 preliminary preparation.

The plate 10 then has its reduced edge portions 11 at three sides cut off as waste, so as to perfect the corresponding printing 25 margin of the cut, but the top reduced portion is left and remains as a relatively thin flange 14, Fig. 2. Ordinarily tacks are driven through this flange 14 and into a lead base or it is cemented to the base or otherwise secured, but under the present invention 30 the reduced flange 14 is bent backwardly, as in Fig. 3, so as to provide a right-angled back flange 15. Preferably the backwardly bent flange 15 is approximately one-half inch across its shortest dimension.

35 Under the present invention a steel or other hard metal base block 16 may be employed on which to mount the photo-engraved cut, but this block is somewhat shorter than the length of the lead blocks 40 customarily employed, because it is not intended to nor can the photo-engraved cut be tacked to such hard metal block. The length of the base block 16 to afford sufficient length of area to properly support the 45 photo-engraved printing plate 10, 15, is extended under the present invention by the use of a simple piece of type furniture 17 (see Fig. 4), constituting a supplemental or auxiliary base block, and the furniture 17 50 is of the same height or depth as the base block 16 so that when it is set up in a chase with the base block their upper surfaces will be flush with each other. Furthermore, the length of the simple piece of furniture 17 55 corresponds with the width of the base block 16, but it can be made of any desired material or metal and does not have to be of the same metal as the base block 16. The improved piece of furniture 17 is provided 60 with a longitudinal rabbet groove 18 at its upper outer corner with respect to the base block, and this groove is relatively deep as compared with its dimension at right angles to its depth.

65 The method of use of the means herein

described and illustrated, so far as not described, is as follows:

The base block 16 and the piece of furniture or auxiliary base block 17 are placed in the desired position in the chase, and type 70 19, 20 together with the column rules, leads, quoins, etc. are arranged in the chase around the members 16, 17 in the usual manner customary in newspaper work, just as if the members 16, 17 were one base member. 75 There will then be formed between the rabbet groove 18 in the piece of furniture 17 and the adjacent wall of the line of type or lead a correspondingly long but deep and thin groove or pocket, as shown in Fig. 5. 80 The form is then locked up. The photo-engraving plate 10 including its right-angled back flange 15 is then taken hold of and presented towards the form about as indicated in dotted lines in Fig. 5; that is to say, the plate 10 is held substantially parallel with the base block 16 and the piece of furniture 17, and the flange 15 is brought substantially in registration with the pocket formed at the recess 18, and the flange is 85 then moved under slight pressure into the pocket or recess until its edge rests upon the shoulder formed at the bottom of the rabbet groove 18, the body of the plate 10 being 90 then supported upon the block 16 and the piece of furniture or auxiliary block 17. Preferably the gage of the thickness and the length of the flange 15 are such that it requires slight pressure to engage said flange 95 in the pocket or recess. In this manner the photo-engraving plate 10 is firmly and securely supported upon the foundation provided by the block 16 and the piece of furniture or auxiliary block 17, and in the use 100 of the form the flange 15 cannot move out of the pocket or recess provided for it. To withdraw the plate 10 it is necessary to draw the flange 15 vertically out of the pocket or recess in the form, a slight pull being 105 necessary, when the form is locked up. The flange 15 being cut the full width of the base block, is kept from sliding laterally by the column rules or other type make-up.

110 It is obvious that the invention may be applied in job printing offices which make use of flat presses for commercial printing, and the plate 10 and its back flange 15 may be applied to the form before the type and other matter are locked up; and obviously the invention may be otherwise utilized and modified without departing from the spirit thereof as expressed in the scope of the appended claims.

115 What I claim as new is:

120 1. The herein-described method of preparing and mounting photo-engravings, which comprises etching a metal plate to form a cut, forming a relatively thin flange on the plate at the top of the cut in removing all other waste metal beyond the edges of 125 130

the cut to leave the finished photo-engraving, bending the flange back, where it joins the cut, at right angles to the back of the cut, providing a base-block and a longitudinally 5 rabbet-grooved strip-like piece of furniture of same height and length as the width of the base-block, fitting the ungrooved high side of the piece of furniture to the top edge of the base-block, setting up in the 10 form the type and furniture which is to adjoining the base-block and said strip-like piece of furniture, thereby providing a groove between the set up matter and the strip-like piece of furniture, and inserting the flange 15 of the cut into the groove by moving the cut directly toward and parallel with the set up matter.

2. The herein-described method of preparing and mounting photo-engravings, 20 which comprises etching a metal plate to form a cut, forming a relatively thin flange on the plate at the top of the cut in removing all other waste metal beyond the edges

of the cut to leave a finished photo-engraving, bending the flange back, where it joins the 25 cut, at right angles to the back of the cut, providing a base-block and a singly longitudinally rabbet-grooved strip-like piece of furniture in which the groove is approximately as thin as the flange of the cut, fitting the ungrooved high side of the said 30 piece of furniture to the top edge of the base-block, setting up in the form the type and furniture which is to enclose the base-block and said strip-like piece of furniture, thereby providing a groove between the set 35 up matter and the strip-like piece of furniture, locking up the form thereby defining a groove which is adapted to obtain a friction fit of said flange therein, and moving the cut directly towards and parallel with the set up matter with the flange in registration with said groove, and forcibly pushing said flange into said groove while the form is locked.

HARRY J. COLEMAN.
